US00D635524S

(12) **United States Design Patent**
Bodenmeier et al.

(10) **Patent No.:** **US D635,524 S**
(45) **Date of Patent:** **** Apr. 5, 2011**

(54) **BASIC BLOCK FOR MOUNTING OF
INSTALLATION DEVICES**

(75) Inventors: **Martin Bodenmeier**, Parkstein (DE);
Thomas Detempele, Planegg (DE);
Manuela Lüftl, Amberg (DE); **Peter Trautwein**, München (DE)

(73) Assignee: **Siemens Aktiengesellschaft**, Munich (DE)

(**) Term: **14 Years**

(21) Appl. No.: **29/347,642**

(22) Filed: **Mar. 24, 2010**

Related U.S. Application Data

(62) Division of application No. 29/290,020, filed on Oct. 12, 2007, now Pat. No. Des. 615,502.

(30) **Foreign Application Priority Data**

Aug. 6, 2007 (EM) 000777461

(51) **LOC (9) Cl.** **13-03**

(52) **U.S. Cl.** **D13/173; D13/158**

(58) **Field of Classification Search** D13/123, D13/133, 146, 147, 154, 158, 178, 184, 199; 439/164, 259, 262, 310, 338, 344, 378, 379; 285/9.2, 81, 284.1, 286.1, 324, 412
